The ornamental design for a tomahawk mailbox flag, as shown and described.

DESCRIPTION

FIG. 1 is a right-side elevational view of a tomahawk mailbox flag showing my new design;
FIG. 2 is a left side elevational view thereof;
FIG. 3 is a rear elevational view thereof;
FIG. 4 is a front elevational view thereof;
FIG. 5 is a top plan view thereof;
FIG. 6 is a bottom plan view thereof; and,
FIG. 7 is a right-side elevational view showing the flag mounted; the broken line showing of the mailbox is for illustrative purposes and forms no part of the claimed design.
